ABSTRACT

Apparatus for stacking labels or the like, employing cooperative apparatus that advances the individual labels successively to stacking comb means, where the previously advanced and stacked labels are momentarily elevated on a specially controlled basis, for insertion of the individual label beneath the stack portion and above the comb means, with unique reciprocated control means on the forming stack.

LABEL STACKING

RELATED APPLICATIONS

This application is related to copending application, Ser. No. 807,894 filed Mar. 17, 1969, now U.S. Pat. No. 3,601,950, issued Aug. 31, 1971, and entitled "Label Handling and Stacking Apparatus."

BACKGROUND OF THE INVENTION

This invention relates to label handling apparatus, and more particularly to apparatus cooperable with a label cut and fold mechanism for automatically and controllably forming stacks of labels or like articles as for packing into containers.

In the manufacture of clothing labels, the label stock is normally initially advanced in the form of a ribbon or strip, and is then cut into individual labels. Commonly, these cut labels are folded with an end fold, a center fold, a miter fold, or some other fold configuration, as well as sometimes remaining unfolded. They are then stacked and packed into containers, e.g., elongated trays and/or cartons.

In the above identified copending patent application is disclosed apparatus for automatically stacking and packing such items. Such apparatus has been found extremely useful for eliminating certain tedious and time consuming manual operations. Further, it has been found that such apparatus is capable of handling labels at more rapid production rates than previously. However, it was discovered that, at the extremely rapid stacking rates of which the apparatus was capable, the forming label stack sometimes became somewhat disorganized, even though retained within the vertical guide elements at the label corners. Hence, full potential of the apparatus could not be realized.

SUMMARY OF THE INVENTION

It is an object of this invention to provide an apparatus for automatically stacking small sheetlike articles, particularly labels for clothing and other cloth goods, at very high output rates, from a label cut and fold machine, while retaining the forming stack in constant neat array. The individual labels are rapidly advanced and inserted beneath the forming label stack which is momentarily elevated and then lowered again before reelevation with the added label as part of it. The improved apparatus incorporates a relatively simple and inexpensive, yet highly effective stack retainer device that maintains stack organization during high speed vertically reciprocating movement of the stack during its formation, yet allows vertical stack discharge.

The stacking apparatus, employing the combination of 50 comb supports interleaved with elevating fingers and receiving individually advanced labels inserted beneath an elevated stack, has a special vertically shiftable stack retainer and stabilizer device on the top of the forming stack. The retainer means is shiftable upwardly and downwardly with the elevating stack in synchronism therewith, in a path causing it to repeatedly stabilize the stack during vertical reciprocation, and move out of the stack path during discharge.

These and other objects and features of this invention will become apparent upon studying the following description.

BRIEF DESCRIPTION OF THE DRAWINGS

FIG. 1 is a fragmentary top perspective view of the label stacking combination;

FIG. 2 is a perspective view of the stack stabilizer for the apparatus, and its mount;

FIG. 3 is a front end elevational view taken on plane III-III of FIG. 1; and

FIG. 4 is a side elevational view of the apparatus taken on plane IV-IV of FIG. 3.

DESCRIPTION OF THE PREFERRED EMBODIMENT

The combination of this invention employs the apparatus disclosed and explained in the above identified copending ap-

75

plication, but with mechanism 310 (see especially FIG. 2 herein) mounted thereto as illustrated in FIGS. 1, 3, and 4 herein, to cooperate uniquely in combination therewith. In other words, the total combination 8 herein involves apparatus 10 with mechanism 310 mounted thereon.

In normal usage of the combination, preceding steps to those of particular concern herein regularly include advancement of a label strip constituting a plurality of integrally interconnected, like printed labels or the like, label cutting functions to separate the individual labels, and label folding steps, followed by label ironing and advancing to the stacker. All of these operations are disclosed in the above identified copending application, while in this present application the novel features lie in the stacking mechanism that receives the labels from the advancing portion of the apparatus.

During operation of the apparatus, as explained in the previous application, ironing and advancing of the labels occur generally simultaneously, employing supports 121, ironers 119, and label advancing gripper bars 116 and 118, which are all elongated cooperative members extending from the label cutoff zone (not shown) to the label stacking subassembly 18. The vertically reciprocating ironers 119 are suspended on the lower ends of support rods, e.g., 119a, the upper ends of which engage cams, e.g., 199f on camshaft, e.g., 198a.

Gripper bars 116 and 118 cooperate with supports 121 and ironers 119, which laterally straddle the bars 116 and 118. Ironer strips 119 support the series of labels being advanced, one behind the other, by having the label edges resting on these ironers. Gripper bars 116 and 118 move in four directions in the manner indicated by the arrows in FIG. 4. They first vertically move together to grip the center portions of the series of sequential labels (during which the labels are ironed), shift forwardly toward the stacker subassembly 18 to 25 simultaneously advance the labels a sufficient distance for another label to be deposited at the tail end of the line, vertically move apart to momentarily lay the labels on ironers 119, and then reverse to the starting position for repeat of this sequence. These movements of gripper bars 116 and 118 are 30 as set forth in the above identified copending application. In so doing, the individual labels are sequentially advanced to the comb elements of the stacking subassembly.

Specifically, as each individual label L is advanced to stacker subassembly 18, it is deposited by gripper bars 116 and 118 on a fixed-comb-type support 180 which includes a base 182 and a plurality of spaced, generally parallel, upright, transversely oriented plates 184. Successive labels are sequentially individually deposited on this comb formed by the upper edges of these plates, with the previously deposited labels being temporarily elevated while the new label is inserted underneath them and on comb plates 184. Hence, a stack is formed by adding labels repeatedly to the bottom of it. These labels are elevated off plates 184 by shifting spaced, plate type groups of fingers 186 and 186' which project between plates 184 from opposite sides of the comb, and initially beneath the upper surface formed by plates 184. With a special movement, to be described hereinafter, these fingers momentarily rise above this upper surface to lift the forming stack of labels sufficiently to allow another one to be deposited therebeneath, and then drop the labels down again on the newly deposited label, by the fingers moving downwardly in reverse direction. This action is then repeated.

Fingers 186 and 186' are mounted at the outer ends thereof to supports 190 and 190', respectively. These supports are attached to the lower ends of a pair of pivot arms 192 and 192', respectively, pivotally mounted on shafts 194 and 194', respectively. Pivot arms 192 and 192' each have an L-shaped configuration, with the two legs of the L extending on both sides of shafts 194 and 194', and having respective cam followers 196 and 196' on the ends thereof that are opposite the ends which support fingers 186 and 186'. A pair of rotational cams 198 and 198' on camshafts 198b and 198a cause these pivot arms or levers 192 and 192' to arcuately reciprocate during rotation of the cams, moving the plate like groups of

fingers 186 and 186' inwardly and upwardly to elevate all labels thereon, i.e., the forming stack, and then downwardly and outwardly to lower the labels onto the newly deposited label on plates 184.

Shafts 198a and 198b, spaced and parallel with respect to each other, are mounted by suitable pillow blocks 314 to the pair of elongated, spaced, parallel, overhead support members 312 and 312'.

Above the stacking comb means is a plurality of four label stack guide elements 252a, 252b, 252c, and 252d, explained in detail in the copending application. The individual labels L, when elevated during stacking and when elevated during stack discharge, are guided by these elements. The elements can be laterally adjusted to accommodate a wide label, as in the position illustrated in FIG. 3, or to positions accommodating smaller labels, as illustrated in FIG. 1.

Cooperative with the stacking means, and forming a part thereof, and more specifically, cooperative with comb 180, with the lifting sets of fingers 186 and 186', and with the guides 252a-d is the novel mechanism 310. This mechanism includes a slide member 320 in the slide guide 322, the latter forming part of a mount 324. Mount 324 has a pair of oppositely extending bifurcated portions 324a and 324b for attachment by suitable bolts 325 to the supports 312' and 312. The center portion of mount 324 extends forwardly toward the discharge or stacking end of the machine, generally overlying the slot 311 between mounts 312 and 312'.

Slide guide 322 is oriented generally vertically, slightly diagonally with the lower end oriented toward, but not overlying, the label stack area defined by the guides 252a-d. Slide 320 constitutes an elongated member slidably mounted in guide 322, having a stop 328 at the upper end thereof to limit downward movement in the guide 322, and having a foot 330 on the lower end thereof to engage the top of the label stack. Foot 330 has its lower surface preferably lying in a horizontal plane, thereby being diagonally oriented relative to the main body of guide 320 due to the diagonal vertical orientation of slide 320 and guide 322. Slide 320 can therefore generally move from a lowermost position with stop 328 abutting the upper ends of guide 322, to an uppermost position with foot 330 abutting the lower surface of guide 322. In its most elevated position, and approximately one-third of its travel downwardly, the slide foot 330 at the base of the slide is outside the zone or area defined by the guides 252a-d so as not to overlie the labels L within the guides. In the lowermost position of the slide, and approximately the lowermost two-thirds of its travel, the lower end of the slide extends over the label zone. Hence, when the stack is initially forming, and until it reaches the desired height of the stack so as to contain a predetermined number of labels, foot 330 of the slide will remain in resting engagement with the top of the label stack. Further raising of the label stack will cause the slide to move horizontally rearwardly sufficiently that foot 330 is out of engagement with the stack. This enables the stack to be hoisted by elevator 256 into a carton positioned around the guides 252a-d. Operation of elevator 256 is set forth in the above identified copending patent application. Hence, the special turntable mechanism 20 explained in detail in the copending application, with its stack elevating and packing device 256, can be advantageously employed without interference from novel mechanism 310. Elevator 256 is operated by a power actuator or motor, such as a fluid cylinder, all as set forth in the identified copending application. This occurs after the elevator finger is inserted beneath the stack while the stack is momentarily partially elevated by fingers 186 and 186'.

Stated otherwise, as the individual labels are being added to the stack at the bottom thereof, by momentary, limited, temporary elevation of the stack with fingers 186 and 186', the stack is not lifted sufficiently to cause foot 330 of the stack retainer mechanism to move sufficiently horizontally to disengage the stack. During high speed vertical reciprocation of the forming stack, the sliding stack retainer 320 stabilizes the stack during rapid elevation by inwardly and upwardly moving

fingers 186 and 186', and stabilizes the stack during subsequent rapid lowering of the stack with downwardly and outwardly arcuate movement of these lifting fingers. The stack is thereby prevented from spreading apart and becoming disheveled during the high speed reciprocation. When the stack is of desired height, it is further elevated to be discharged from the guides and into a receptacle. In spite of the simplicity of this device, it has been found to work extremely well. Furthermore, when the hoisting mechanism 256 for the packer assembly 20 is elevated rapidly, the retainer resting upon the label stack presents no hindrance to rapid discharge of the labels from guides 252a-c and insertion of the label stack upwardly into the carton supported on the guides 252a-d.

In operation therefore, after the label strips are cut, and if desired, folded, they are individually advanced by grippers 116 and 118 in cooperation with ironers 119 and supports 121, each label being successively deposited on the plates 184 of comb 180, and preceding deposited labels in the forming stack being momentarily elevated by the arcuate inward and upward movement of fingers 186 and 186' while the gravity bias on stack retainer mechanism causes foot 330 of slide 320 to engage the upper end of the label stack during elevation and relowering of the stack on the newly deposited label. When the stack reaches a predetermined number of labels, the packer mechanism and specifically the stack elevating finger 256 is actuated in controlled fashion to engage the bottom label in the stack and hoist the stack of labels up within guides 252a-d and into a carton. This causes the retainer slide 320 and foot 330 to move not only vertically, but laterally out of engagement with the top of the label stack to prevent its hindering the packing operation. With relowering of finger 256 of the packer, gravity lowers slide 320 and foot 330 of mechanism 310 to cooperate with the subsequently forming label stack.

This particular apparatus has been found to be uniquely advantageous for this particular assembly. It is also conceivable that it might be modified in various respects to suit modified label or other like article handling mechanisms. In addition, various additional advantages and features not specifically recited may be obvious to those skilled in this art upon reading this disclosure. Hence, the invention is intended to be limited only by the scope of the appended claims and the reasonable equivalents thereto.

The embodiments of the invention in which an exclusive property or privilege is claimed are defined as follows:

1. Stacking apparatus for small sheet items such as labels employing sheet item stack support means having a stacking zone, stack elevating means at said zone cooperable with said support means to momentarily elevate stacked sheet items from said support means a limited amount and subsequently lower them again and, means to further depositing said stack for discharge thereof, individual item advancing and depositing means for depositing sheet items on said support means in said zone beneath momentarily elevated stacked items, the improvement comprising stack stabilizer mechanism having a downwardly biasing stack engaging portion in said zone, and being vertically movable upwardly and downwardly with stacked items to stabilize them; said stabilizer mechanism being guided to be movable through a first elevated region with said stack engaging portion aligned with said zone, but further elevation of said portion causes said portion to move out of alignment with said zone to enable vertical removal of a stack from said zone.

2. The stacking apparatus in claim 1 wherein said zone is defined by vertical guides for the stacked items.

3. The stacking apparatus in claim 1 wherein said stabilizer mechanism is arranged to have diagonal motion of said portion with both vertical and horizontal components, controlling said movements both in alignment with and out of alignment with said zone.

4. The stacking apparatus in claim 2 wherein said stabilizer mechanism includes a slide member and guide means

therefor, both being oriented diagonally downwardly toward said zone, said stack engaging portion being on said slide member and movable from a lowered region above said zone to a raised region not above said zone.

5. The stacking apparatus in claim 4 wherein said slide 5 member is gravity biased toward said zone.
